UNITED STATES PATENT OFFICE.

WILLIAM BOSTICK, OF NORTH BRADDOCK, PENNSYLVANIA.

WRENCH.

1,003,426.

Specification of Letters Patent. Patented Sept. 19, 1911.

Application filed August 15, 1910. Serial No. 577,135.

To all whom it may concern:

Be it known that I, WILLIAM BOSTICK, citizen of the United States, residing at North Braddock, in the county of Allegheny and State of Pennsylvania, have invented 5 certain new and useful Improvements in Wrenches, of which the following is a specification.

This invention relates to wrenches of the 10 quick adjusting variety, and the principal object is to provide a quick adjusting wrench which may be readily adjusted and operated with one hand.

Another object is to provide a quick acting 15 wrench of simple construction and at the same time as durable as the ordinary wrench.

With these and other objects in view which will be more fully set forth in the 20 following specification, I have devised the wrench illustrated in the accompanying illustrations, in which,

Figure 1 is a side elevation of the wrench proper partially closed, Fig. 2 is a similar 25 view showing the wrench opened wider, Fig. 3 is a side elevation of a modified form of the wrench, and Fig. 4 is a cross sectional view taken on the line A—A of Fig. 3.

In the accompanying drawings and the 30 specification, like characters of reference refer to like parts throughout, and 1 indicates a wrench having either an integral or a separable handle 2, to this handle is secured the fixed member 3, having on one 35 end a bearing socket 4 to which is pivoted a movable member 5. On the forward end of the fixed member 4 is an integral jaw 6 having a right angled extension 7 which forms a strap through which passes the movable member 5, to the outer end of which is a movable jaw 8. Resting on the top of the movable member 5 and slidable thereon is a locking wedge member 9 having a rack 10 on the upper inclined surface thereof. 40 This wedge slides through the slot formed by the strap 7 which has teeth 11 on the upper part thereof.

Secured to one end of the wedge member 50 is a strap 12 which straddles the two jaw members. In the movable jaw is a slot 13 parallel with said member. In this slot works a pin 14 which is secured to both sides of the strap 12. In the fixed jaw member is an inclined slot 15 in which operates a pin 16 which is also secured to both

sides of the said strap. The incline of the slot 15 is equal to or parallel with the incline of the racked surface of the wedge member 9. The movable jaw member has a right angled extension 17 in which is a 60 slot 18 through which passes the pin 19 which loosely connects the two jaw members.

20 is a thumb rest by which the sliding wedge is ordinarily operated. 65

21 is a spring which holds the movable jaw normally in a raised position.

In operation the jaws of the wrench are separated as shown in Fig. 2, the wrench is held by the handle 2 and the jaws placed 70 over a nut, the thumb of the operator is placed on the inclined portion 20 of the sliding wedge member which is then forced forward as far as possible which closes the jaws over the nut, the teeth 11 on the strap 75 7 engage the rack 10 and holds it in a locked position and so tightly wedged that it will be impossible to give the slightest particle; the jaws at the same time being absolutely parallel to the sides of the nut, 80 which they contact. The action of the pins 14 and 16 working in the slots 13 and 15 is to raise and lower the back end of the movable jaw member 5, thereby moving the entire jaw on a parallel line. 85

In Fig. 3 a modification is shown in which the sliding wedge member is secured at the rear end to a member 22 which is dovetailed to the grooves 23 and 23' of the movable jaw member 24 by the inturned ends 26 and 26' 90 thereof. The bottom of this member is joined at an angle parallel to the angle of the rack edge of the wedge member 9, and the socket bearing 27 has an inclined upper surface which is also parallel with the incline of the wedge member and the member 22, by this arrangement the jaws of the wrench may always be kept parallel. 95

Other modifications may be made without departing from the spirit of the invention. 100

Having described my invention, I claim and desire to secure by Letters Patent:

1. In a wrench a handle, jaw members parallel therewith, a sliding wedge adapted to hold said jaw members in relative position, 105 means by which said jaw members are held in constant parallel relation, straps connecting said members, one of said members being movable, said wedge being seated upon said movable jaw, said wedge having ser- 110

rations upon its inclined surface and means for engaging said serrations whereby said wedge will be held in fixed position.

2. In a wrench, a handle, jaw members parallel therewith, a sliding wedge adapted to hold said jaw members in relative position, means by which said jaw members are held in constant parallel relation, straps connecting said members, one of said members being movable, said wedge being seated upon said movable jaw, said wedge having serrations upon its inclined surface, and a tooth on one of said straps adapted to engage said serrations.
15. 3. In a wrench, a handle, jaw members parallel therewith, a sliding wedge adapted to hold said jaw members in relative position, means by which said jaw members are held in constant parallel relation, straps connecting said members, one of said members being movable, said wedge being seated upon said movable jaw, said wedge having serrations upon its inclined surface, a tooth on said straps adapted to engage said serrations, and a spring adapted to hold said jaws normally apart.
4. In a wrench, a handle, jaw members parallel therewith, a sliding wedge adapted to hold said jaw members in relative position, means by which said jaw members are held in constant parallel relation, straps connecting said members, one of said members being movable, said wedge being seated upon said movable jaw, said wedge having serrations upon its inclined surface, a tooth

on said straps adapted to engage said serrations, a spring adapted to hold said jaws normally apart, and inclined planes upon said members.

5. In a wrench, a handle, jaw members parallel therewith, a sliding wedge adapted to hold said jaw members in relative position, means by which said jaw members are held in constant parallel relation, straps connecting said members, one of said members being movable, said wedge being seated upon said movable jaw, said wedge having serrations upon its inclined surface, a tooth on said straps adapted to engage said serrations, a spring adapted to hold said jaws normally apart, and inclined planes upon said members, said planes being oppositely disposed.

6. A wrench having a fixed jaw member, and a movable jaw member, a strap on said fixed jaw member, said strap straddling said movable jaw member, a sliding wedge, for locking said sliding jaw member, a strap secured to said wedge, pins on the strap secured to said wedge, said pins operating in grooves in said jaw members for raising and lowering said movable jaw member in parallel relation to said fixed jaw member.

In testimony whereof I affix my signature in presence of two witnesses.

WILLIAM BOSTICK.
